UNITED STATES PATENT OFFICE.

JOSEPH B. SHAINLINE, OF NORRISTOWN, PENNSYLVANIA.

FLYING-MACHINE.

983,940.

Specification of Letters Patent. Patented Feb. 14, 1911.

Application filed March 28, 1910. Serial No. 551,972.

To all whom it may concern:

Be it known that I, JOSEPH B. SHAINLINE, a citizen of the United States, residing at Norristown, in the county of Montgomery 5 and State of Pennsylvania, have invented certain new and useful Improvements in Flying-Machines, of which the following is a specification.

My invention relates to improvements in 10 flying machines, the object of the invention being to provide an automatically controlled equilibrium of the machine, in which equilibrium planes are positively moved by the engine when the machine tilts to bring it back 15 to an even keel.

A further object is to provide a flying machine with improved means for moving the equilibrium planes, said means moved into and out of operation by a swinging or 20 pivoted pendulum.

With these and other objects in view, the invention consists in certain novel features of construction and combinations and arrangements of parts as will be more fully 25 hereinafter described and pointed out in the claims.

In the accompanying drawings: Figure 1, is a top plan view. Fig. 2, is a view in side elevation. Fig. 3, is a view in front elevation. Fig. 4, is a view in section on the line 30 4, 4, of Fig. 2, and Fig. 5, is an enlarged broken view of my improved gearing.

1, represents a central frame, 2 side wings, 3 a tail, and 4 and 5 horizontal and vertical 35 rudders at the end of the tail. The tail is shown strengthened by a longitudinal and transverse braces 6 and 7 respectively, and wheels 8, and a runner 9 are illustrated to contact with the ground.

40. The parts above described are shown merely to illustrate one application of my improvements, and my invention is in nowise limited to this particular type of machine.

At the ends of the side wings 2, equilibrium planes 10 are pivotally supported between their ends to swing up and down at their front and rear ends, and a third equilibrium plane 11, is pivotally supported in uprights 12, at the front and rear of the 45 frame, and is adapted to swing up and down at its side edges. The purposes of these equilibrium planes is to compel the machine to right itself when tilted and my improvements which will now be described, 50 are designed to positively and automatically move the equilibrium planes.

Hangers 13, depend from the upper part of frame 1, and support a shaft 14, on which a drum 15, is mounted to turn and a gear wheel 16 is secured to turn with the drum. 60

A wire or other flexible connecting device 17, is secured at one end to the forward end of one plane 10, thence around drum 15, secured to the latter, and thence to, and secured to, the rear end of the other plane 10. 65 A wire 18, connects the front end of the last-mentioned plane 10, with the rear of the first-mentioned plane, to compel the planes to operate reversely, that is when the forward end of one plane 10, is drawn down, 70 the forward end of the other will be elevated. A wire 19, is secured to one side of plane 11, is then passed down and around, and secured to, the drum 15, and thence extends up to and is secured to the other side 75 of said plane 11, so that when said drum is turned, not only will planes 10 be moved but also plane 11.

An inverted T-frame 20, is pivotally supported on shaft 14, and a horizontal frame 80 21 is secured upon a shaft 22, mounted in the vertical members of said frame 20. This shaft 22 has a crank arm 23 at one end, connected by a link 24, with the upper end of a lever or pendulum 25, pivotally supported 85 at one end of frame 20, and having a weight 26 at its lower end to maintain the lever in vertical position. Frame 21 supports two intermeshing pinions 27, both of which are normally out of mesh with gear 16, but 90 either adapted to be moved into mesh therewith. One of these pinions 27, is turned by a flexible shaft 28, operated by the motor 29, which turns shaft 30, and propeller 31. 95

A hand lever 32 fulcrumed to a bracket 33, on frame 1, is also connected by a link 34, with T-frame 20, at the end opposite to the point of pivotal attachment of pendulum 25, so that frame 20, may be manually moved. 100 The purpose of this lever is to move inverted T-frame 20, around on shaft 14, so as to make inverted T-frame 20 hang at a different angle with the main frame of the flying machine, thus making the machine tip at 105 an angle that will bring vertical bar of the inverted T-frame 20, in line with the pendulum. This lever 32 is to be used only in rounding curves. When turning to the right or left, the machine will tip, so that the side 110 on the outside of the curve will be elevated above the opposite side.

The operation is as follows: When the machine tilts to one side, the movement of pendulum 25 at an angle to its normal position, through the medium of link 24, 5 crank arm 23, shaft 22, and frame 21, moves one of the pinions 27 into mesh with gear 16, to turn drum 15, as the pinions 27 are being continuously turned by shaft 28, the pinion 27, gear 16 and drum 15, will move wires 17 10 and 19, to change the angles of planes 10, and 11, and compel the machine to automatically right itself. The direction of movement of the planes depends on which pinion 27 is moved into mesh with gear 16, 15 and this is controlled automatically by pendulum 25.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. In a flying machine, the combination with supporting wings and a central frame, 30 of a drum on the frame, equilibrium planes, wires connecting the drum with said planes, a gear constructed to turn with the drum, intermeshing continuously turning pinions, and means for moving either of said pinions 35 into mesh with the gear, substantially as described.

2. In a flying machine, the combination with supporting wings and a central frame, of a drum on the frame, equilibrium planes, 40 wires connecting the drum with said planes, a gear constructed to turn with the drum, intermeshing continuously turning pinions, and a swinging pendulum constructed to move either of said pinions into mesh with 45 the gear, substantially as described.

3. In a flying machine, the combination with supporting wings and a central frame, of a drum on the frame, equilibrium planes, wires connecting the drum with said planes, 50 a gear constructed to turn with the drum, intermeshing continuously turning pinions, a pivotal frame supporting said pinions, and means for tilting the latter frame to move either of the pinions into mesh with the 55 gear, substantially as described.

4. In a flying machine, the combination with supporting wings and a central frame, of a drum on the frame, equilibrium planes, wires connecting the drum with said planes, 60 a gear constructed to turn with the drum, intermeshing continuously turning pinions, a pivotal frame supporting said pinions, and

a pendulum constructed to tilt the latter frame to move either of the pinions into mesh with the gear, substantially as de- 65 scribed.

5. In a flying machine, the combination with a central frame, side wings secured to the frame, and equilibrium planes connected to the wings, and frame, of an inverted T- 70 frame pivotally supported in the main frame, a drum in the main frame, a wire secured to the respective planes and to the drum, a gear on the drum, a horizontal frame pivotally supported between its ends, 75 intermeshing pinions on the horizontal frame, a motor, a flexible shaft connected to the motor and driving one of the pinions, and means for tilting said horizontal frame to move either of said pinions into mesh 80 with the gears, substantially as described.

6. In a flying machine, the combination with a central frame, side wings secured to the frame, and equilibrium planes connected to the wings, and frame, of an inverted T- 85 frame pivotally supported in the main frame, a drum in the main frame, a wire secured to the respective planes and to the drum, a gear on the drum, a horizontal frame pivotally supported between its ends, 90 intermeshing pinions on the horizontal frame, a motor, a flexible shaft connected to the motor and driving one of the pinions, a crank shaft supporting the horizontal frame, a pendulum connected to one end of the T- 95 frame, and a link connecting the pendulum and crank shaft, substantially as described.

7. In a flying machine, the combination with a central frame, side wings secured to the frame, and equilibrium planes connected to the wings, and frame, of an inverted T- 10 frame pivotally supported in the main frame, a drum in the main frame, a wire secured to the respective planes and to the drum, a gear on the drum, a horizontal 11 frame pivotally supported between its ends, intermeshing pinions on the horizontal frame, a motor, a flexible shaft connected to the motor and driving one of the pinions, a crank shaft supporting the horizontal 11 frame, a pendulum connected to one end of the T-frame, a link connecting the pendulum and crank shaft, a pivoted hand lever, and a link connecting said hand lever with the other end of the T-frame, substantially 1 as described.

In testimony whereof I have signed my name to this specification in the presence of two subscribing witnesses.

JOSEPH B. SHAINLINE.
